CLAIM

The ornamental design for a cash register or similar article, as shown and described.

DESCRIPTION

FIG. 1 is a perspective view taken from the top, front and right side of a cash register or similar article showing our new design;

FIG. 2 is a front elevational view thereof;

FIG. 3 is a rear elevational view thereof;

FIG. 4 is a right side elevational view thereof; and

FIG. 5 is a left side elevational view thereof;

FIG. 6 is a top plan view thereof;

FIG. 7 is a perspective view taken from the top, front and right side of a modified form of the cash register or similar article shown in FIG. 1.

The broken line showing of indicia in FIGS. 1 and 7 is for purposes of illustration only and forms no part of the claimed design.
